UNITED STATES PATENT OFFICE.

EMIL FRANK, OF CINCINNATI, OHIO.

POWDER-PACKAGE.

1,282,209.

Specification of Letters Patent.

Patented Oct. 22, 1918.

Application filed June 27, 1918. Serial No. 242,254.

To all whom it may concern:

Be it known that I, EMIL FRANK, a citizen of the United States, and residing at Cincinnati, in the county of Hamilton and 5 State of Ohio, have invented a new and useful Improvement in Powder-Packages, of which the following specification is a full disclosure.

My invention relates to a powder package of cardboard or the like, made from a 10 single blank, adapted to be folded into a triangular package of about one inch or less in thickness, of substantially bellows-like structure, having a nozzle projection to 15 be punctured.

The invention constitutes an improvement over the device disclosed in my copending application, Serial No. 197,608, filed Oct. 20, 1917, since patented as Patent No. 1,276,- 20 204, dated August 20, 1918, the object of 20 the present invention being to improve the structure of the package in binding, cheapen the cost and render the same more efficient.

25 The features of the invention are more fully set forth in the description of the accompanying drawings, forming a part of this specification, in which:—

Figure 1 is a plan view of the blank.

30 Fig. 2 is a plan view of one of the margin bindings.

Fig. 3 is an end view of the formed package.

Fig. 4 is a top plan view of the package, 35 showing the bindings of Fig. 2 applied to the marginal edges of the package.

The blank, Fig. 1, is a substantially diamond-shaped cardboard formed with the medial transverse scored line 2, enabling the 40 right and left hand wings to be folded upon one another in triangular formation. The package is given cubic dimensions by folding marginal sides of the sections 12, 13, 14, 15, defined by scored lines 3, 4, 5, 6, and by 45 two base sections 16, 17, on opposite sides of line 2 defined by folding lines 7, 8, parallel with lines 2. The ends 9, 10, of the side pieces 11, 11, are cut off straight to squarely abut when the blank is folded; and 50 to constitute the nozzle 40, see Fig. 4, the converging scored lines 3, 4, and 5, 6, terminate at their intersection in outwardly extending scored lines 41, which provide folding lines for the margins 12, 13, 14, 15, 55 at the nozzle end of the structure and when

folded form the nozzle aperture at the lines 9, 10.

The blank at the terminal ends of the transverse scored lines 2, 7, 8, is provided with the notches 18, 19. When the blank is 60 folded on scored lines 2, 7, 8, and the marginal sections 12, 13, 14, 15, are bent in at an angle, the edges of the triangular pieces register and form a box-like structure compressible cross sectionally, the flexibility of 65 the scored lines providing the bellows-like flexibility.

To secure the folded blank into package structure to seal the package and to effect this cheaply without impairing this bellows 70 flexibility, I bind the marginal edges of the several sections with the binding strip 35, Fig. 2, preferably of adhesive paper, and of the shape indicated, having an offset end 36 adapted to be rolled into an approximate 75 cone to cover the apexes of the package. One of these strips is applied to each of the edges so that each corner is sealed and reinforced by the conical portion 36 which caps the corner while the medial line of 80 the strip 35 coincides with the marginal joint edge of the package.

The strip cap 36 folds over and seals the aperture of the nozzle and is to be punctured when the package is to be utilized as a 85 powder ejector.

Having described my invention, I claim:—

1. A compressible powder shipping package and gun of substantially triangular shape, having flat top and bottom walls, 90 angled side walls converging to a medial joint projected beyond the top and bottom, one of the corners being adapted to constitute a nozzle, and binding strips of paper securing the meeting edges of the side walls 95 and having offset ends conically rolled to cap the corners for sealing the package and reinforcing the corners without impairing flexibility.

2. A compressible carton for powder having flat top and bottom walls and outwardly angularly extended side walls, the meeting side edges and corners being sealed by adhesive paper strips having offset ends wrapped around the corners. 100

3. A one-piece cardboard diamond-shaped blank for a powder shipping package and gun, of cardboard, substantially diamond-shaped, said blank being scored diagonally and marginally to allow folding of one 110

triangle section on another, the marginal scored lines providing outwardly angularly extended sides converging to a medial joint, two of the opposite diagonal corners of the blank being squarely cut off, and divisionally scored to provide a nozzle aperture when the blank is folded and secured.

4. A polygonal-shaped powder package and gun, having flat top and bottom and angularly extended sides meeting to constitute a medial flexible joint, one of the

corners forming a nozzle, the medial joint and corners being sealed with adhesive strips said strips having one end offset and rolled around the corner.

In witness whereof, I hereunto subscribe my name, as attested by the two subscribing witnesses.

EMIL FRANK.
